UNITED STATES PATENT OFFICE.

HARRY N. BANEY, OF MUNCIE, INDIANA.

DESIGN FOR A SALT AND PEPPER SHAKER.

Application filed November 17, 1927. Serial No. 24,183. Term of patent 3½ years.

To all whom it may concern:

Be it known that I, HARRY N. BANEY, a citizen of the United States, residing at Muncie, in the county of Delaware and State of Indiana, have invented a new, original, and ornamental Design for Salt and Pepper Shakers, of which the following is a specification, reference being had to the accompanying drawing, forming a part hereof.

The figure is a perspective view of a salt and pepper shaker showing my new design.

I claim:

The ornamental design for a salt and pepper shaker as shown.

HARRY N. BANEY.
